UNITED STATES PATENT OFFICE.

**MELIK FINKLE, OF NEW YORK, N. Y., ASSIGNOR TO THE GEO. H. BOWMAN COMPANY,
OF CLEVELAND, OHIO, A CORPORATION OF OHIO.**

DESIGN FOR A SUGAR BOWL.

Application filed June 7, 1929. Serial No. 31,586. Term of patent 14 years.

To all whom it may concern:

Be it known that I, MELIK FINKLE, a citizen of the United States, and residing at New York, in the county of New York and State of New York, have invented a new, original, and ornamental Design for a Sugar Bowl, of which the following is a specification, reference being had to the accompanying drawing, forming a part thereof, in which—

Fig. 1 is a side elevational view and Fig. 2 is a top plan view of the article showing my new design.

I claim:

The ornamental design for a sugar bowl, substantially as shown.

MELIK FINKLE.
